HAIR CURLER

Louis Eisenman, Brooklyn, N. Y.

Application May 29, 1943, Serial No. 489,050

14 Claims. (Cl. 132—34)

This invention is an improvement over that disclosed in my prior Patent No. 2,328,331, dated August 31, 1943, Hair curler, and relates primarily to hair curlers of that type comprising a rotatable mandrel upon which a lock of hair may be easily and quickly wound and then slipped off the mandrel endwise in a curled condition between the two legs of a bobby pin held by the curler.

One of the objects of the present invention is to provide a hair curler of the above general character which may be easily and conveniently manipulated and which will be reliable and efficient in action and operation.

A further object is to provide a practical hair curler of the above general character which will automatically open the two legs of a bobby pin as the curl is slipped from the mandrel.

A further object will be to provide a hair curler of the above general character having relatively few parts which may be inexpensively manufactured and assembled.

Other objects will be in part obvious from the annexed drawings and in part hereinafter indicated in connection therewith by the following analysis of the invention.

This invention accordingly consists in the features of construction, combination of parts, and in the unique relation of the members and in the relative proportioning and disposition thereof, all as more completely outlined herein.

To enable others skilled in the art fully to comprehend the underlying features of this invention, that they may embody the same by the numerous modifications in structure and relation contemplated by the invention, a drawing depicting a preferred embodiment of the invention forms a part of this disclosure, and in such drawing like characters of reference denote corresponding parts throughout the several views, in which—

Figure 1 is a longitudinal elevational view showing the hair curler in normal position, certain parts being dotted in order to more clearly illustrate the relation;

Figure 2 is a similar view of the same mechanism with the parts in the position where a curl is about to be slipped off the mandrel;

Figure 3 is a detail plan view of one end of the device as shown in Figure 1;

Figure 4 is a detail vertical sectional view taken on the line 4—4 of Figure 3; and

Figure 5 is a transverse sectional view on the line 5—5 of Figure 3.

Fig. 6 is a detailed longitudinal section of one end of the device.

Fig. 7 is a transverse section taken on the line 7—7 of Fig. 6.

5 Referring now to the drawing in detail and more particularly to Figure 1, 10 indicates a mandrel of conventional form provided with a clip 11 which is pivoted at 12 and is adapted to be raised from the mandrel 10 by a downward movement upon the thumb piece 13 thereby to permit a lock of hair to be slipped between the mandrel and the clip in the usual well-known manner prior to rotating the mandrel.

The mandrel 10 is adapted to be rotated freely 15 upon a spindle 14 by means of a knurled finger piece 15 thereby to wind the hair upon the mandrel. At the extreme right of Figure 1 there is shown a clamping member 16 which may have a comb 17, if so desired. The comb is convenient 20 in order to comb out a lock of hair from the head and then reverse the curler thereby to slip the end of the lock of hair between the mandrel and clip 11.

Intermediate the operating member 15 and the 25 part 16 is a fixed stop member 18 pinned to the spindle which limits the movement of the part 15 towards the right and between the parts 16 and 18 is an elongated member 20 which is also rotatably mounted upon the spindle at its right 30 hand end and terminates at its opposite end in a downwardly bent spoon-like portion 21 having a groove 22 in its lower part, the under part of which coacts with a groove 23 in the enlarged portion 24 of the extreme end of the spindle 14 (Fig. 5). This part 24 is provided with a longitudinal and substantially central hole or opening 25 adapted to receive one of the legs 26 of the bobby pin, the other leg 27 being adapted to rest in the recess 22 in the bottom of the spoon 21. 35 The recess 23 which coacts with the groove 22 in the top or upper portion of the enlarged end 24 thus prevents relative movement of the arm under normal conditions. With the upper part of the bobby pin 27 resting in the top of this 40 groove 22, as shown clearly in Figure 2, then the entire construction has a relatively rigid condition when in operation.

The mandrel 10 is hollow on its interior and a 45 collar 31 is rigidly secured in any desired manner to the spindle 14 and acts as an abutment for a spiral spring 32 within the mandrel, the opposite end of which spring coacts with the end wall 33 of the actuating member 15. Thus after the curl is formed and the mandrel is moved relatively 50 towards the left as shown in Figure 2, this spring

is compressed and, on release of the actuating member, this spring returns the parts from the position shown in Figure 2 to the normal position shown in Figure 1.

However, it will be noted particularly that the end of the mandrel 10 is provided with a conical or spherical portion 34 which is adapted to coact with the downwardly inclined part 35 of the member 20 shown in Figure 1. Thus, as the mandrel is moved towards the left, this conical portion 34 tends to wedge under part 35 and raise the same upwardly to the position shown in Figure 2 thereby raising the spoon 21 at the end of the member 20 which in turn carries the upper leg 27 of the bobby pin to provide a space into which the curl 36 is slipped. As soon as this operation is completed then the mandrel is released to move towards the right and the bobby pin clamps onto the curl and this pin, with the curl, may be bodily removed from the device and a new bobby pin inserted as shown in Figure 1, whereupon another curl may be formed and secured.

From the above it will be seen that the present invention provides a simple and practical hair curling device having relatively few parts which may be inexpensively manufactured and assembled. The device is particularly convenient in its ease of operation whereby a curl may be easily and quickly formed upon the mandrel and equally easily and quickly slid off to one side with the curl almost automatically held between the two parts of the bobby pin.

Without further analysis the foregoing will so fully reveal the gist of this invention that others can, by applying current knowledge, readily adapt it for various applications without omitting certain features that, from the standpoint of the prior art, fairly constitute essential characteristics of the generic or specific aspects of the invention, and therefore such adaptations should and are intended to be comprehended within the meaning and range of equivalency of the following claims.

I claim:

1. A hair curling device comprising an elongated spindle of substantially uniform diameter and formed at one end to receive one leg of a bobby pin, a rotatable and longitudinally movable mandrel mounted upon said spindle, a member mounted upon said spindle at one end and extending substantially parallel thereto, the other end of said member being offset towards the spindle and free to move from the spindle when engaged by the mandrel on longitudinal movement, said member having a portion adapted to coact with the other leg of a bobby pin.

2. A device as set forth in claim 1 in which the end of said member is provided with a groove to receive a part of one leg of the bobby pin therein.

3. A device as set forth in claim 1 in which the end of said member is provided with a groove to receive a part of one leg of the bobby pin therein, said groove on its underside being adapted to coact with the end of the spindle thereby to prevent material relative movement.

4. A hair curling device comprising an elongated spindle of substantially uniform diameter and having an opening at one end adapted to receive one leg of a bobby pin, a rotatable and longitudinally movable mandrel mounted upon said spindle, a clamp on said mandrel adapted to temporarily hold a lock of hair while being curled, a member mounted upon said spindle and extending substantially parallel thereto, one end of said

member being offset towards the spindle and free to move from the spindle when engaged by the mandrel on longitudinal movement, said member having a portion adapted to coact with the other leg of a bobby pin, said member and said mandrel adapted to be moved relatively longitudinally whereby such relative movement causes said member to move away from the spindle and simultaneously separate the legs of the bobby pin to permit a curl on the mandrel to be slipped therefrom into position between the legs of the bobby pin.

5. A device as set forth in claim 4 in which the end of said member is provided with a groove to receive a part of one leg of the bobby pin therein.

6. A device as set forth in claim 4 in which the end of said member is provided with a groove to receive a part of one leg of the bobby pin therein, said groove on its underside being adapted to coact with the end of the spindle thereby to prevent material relative movement.

7. A hair curling device comprising an elongated spindle and formed at one end to receive one leg of a bobby pin, a rotatable and longitudinally movable mandrel mounted upon said spindle, means on said mandrel adapted to temporarily hold a lock of hair while being curled, a member extending substantially parallel to said mandrel, one end of said member being offset towards the spindle and free to move from the spindle when engaged by the mandrel on longitudinal movement, said member having a portion adapted to coact with the other leg of a bobby pin, said member and said mandrel adapted to be moved relatively longitudinally whereby such movement will cause the free end of said member to move away from the spindle and simultaneously separate the legs of the bobby pin to permit a curl on the mandrel to be slipped therefrom into position between the legs of the bobby pin and means for holding said member in place on said spindle.

8. A device as set forth in claim 7 in which the end of said member is provided with a groove to receive a part of one leg of the bobby pin therein.

9. A device as set forth in claim 7 in which the end of said member is provided with a groove to receive a part of one leg of the bobby pin therein, said groove on its underside being adapted to coact with the end of the spindle thereby to prevent material relative movement.

10. A hair curler of the character described having a spindle with an opening in one end adapted to receive one leg of a bobby pin and a longitudinally movable mandrel with curling clip on said spindle, an intervening means including a spaced bar with offset ends between the mandrel and the other leg of the bobby pin adapted to separate the legs of the bobby pin to receive a curl when said mandrel is moved longitudinally into engagement with said means.

11. A hair curler of the character described having a spindle with an opening in one end adapted to receive one leg of a bobby pin and a longitudinally movable mandrel on said spindle, and intervening means including a spaced bar with offset ends mounted at one end on the spindle and acting between the mandrel and the other leg of the bobby pin adapted to separate the legs of the bobby pin to receive a curl when said mandrel is moved longitudinally to engage said means.

12. A hair curler of the character described having a spindle with means in one end adapted

to receive one leg of a bobby pin, a freely movable mandrel on said spindle, and an intervening means including a spaced bar with offset ends mounted on the spindle and acting between the mandrel and the other leg of the bobby pin adapted to separate the legs of the bobby pin thereby to receive a curl when said mandrel is moved longitudinally.

13. A hair curling device comprising an elongated relatively slender spindle having a longitudinal opening at one end adapted to receive one leg of a bobby pin, a hollow mandrel mounted upon said spindle and being free to rotate and slide longitudinally thereon, a clip coacting with the mandrel between which clip and mandrel a curl is adapted to be wound, a member substantially parallel to the mandrel and secured at one end to said spindle, its opposite end being free to move relatively away from the spindle, said opposite end having a spoonlike portion with a groove therein extending substantially parallel to the spindle and adapted to receive the other leg of the bobby pin, the under part of said groove coacting with the end of the spindle to prevent relatively rotary movement in normal operation, said mandrel having a conical or pointed end adapted to coact with said spoonlike portion whereby upon movement of said mandrel along

said spindle it coacts with said portion to move the spoonlike portion away from the spindle and permit a curl carried by the mandrel to be slipped between the separated legs of the bobby pin.

- 5 14. A hair curling device comprising an elongated relatively slender spindle having a longitudinal opening at one end adapted to receive one leg of a bobby pin, a hollow mandrel mounted upon said spindle and being freely movable thereon, a clip coacting with the mandrel between which clip and mandrel a curl is adapted to be wound, a member substantially parallel to the mandrel and mounted at one end to said spindle, its opposite end being free to move relatively away from the spindle, said opposite end having a spoonlike portion extending substantially parallel to the spindle and adapted to receive one leg of the bobby pin, the lower part of said portion shaped to coact with the end of the spindle 10 to prevent relatively rotary movement in normal operation, said mandrel having a conical or pointed end adapted to coact with said portion whereby upon movement of said mandrel along said spindle it moves the spoonlike portion away from the spindle to provide a space to receive a curl between the separated legs of the bobby pin.
